UNITED STATES PATENT OFFICE.

MILFORD B. FERGUSON AND EDWARD HAAS, OF BROOKLYN, NEW YORK.

LABEL-AFFIXING APPARATUS.

Application filed March 7, 1919. Serial No. 281,146.

To all whom it may concern:

Be it known that we, MILFORD B. FERGUSON and EDWARD HAAS, citizens of the United States, and residents of the borough of Brooklyn, county of Kings, and State of New York, have invented an Improvement in Label-Affixing Apparatus, of which the following is a specification.

This invention relates to wrapping machinery, and with regard to its more specific features to means for applying wrappers or labels to articles or packages.

One of the objects is to provide a machine of the above type, which shall be simple in construction and reliable in action.

Another object is to provide a machine of the type set forth, which shall neatly, expeditiously and effectively perform its function.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of the several features of this invention,

Fig. 1, is a diagrammatic side view of our machine.

Fig. 2, is a diagrammatic detail view in side elevation showing one step of the operation.

Fig. 3, is a plan view of the detail shown in Fig. 2, and

Fig. 4, is a detail view showing the machine at another stage of its operation.

Similar reference characters refer to similar parts throughout the different views of the drawings.

This invention is particularly concerned with the application of labels to encircle packages, but is also useful for the application of binders or wrappers of paper or the like around either unwrapped articles, or

previously wrapped packages, regardless of whether said binders or outer wrappers bear printed matter, or not.

Referring now to the drawings, we have shown a carrier 1, generally circular in con-

tour, intermittently rotatable about a central axis or shaft 2. The means for causing intermittent rotation of said carrier, is not part of our invention. By way of illustration, we have shown one way of bringing about this intermittent action, which may comprise a driving shaft 3, connected to shaft 2 by a sprocket chain 4, the shaft 3 driving the chain by means of a sprocket wheel 5 bearing a single tooth 5'. It is apparent that rotation is imparted to shaft 2 by chain 4 when tooth 5' is in engagement with the chain, and no such movement is imparted while said tooth is located at the upper half of member 3. The sprocket member 5 is preferably of such diameter, and so timed that the sets of jaws 6, which are mounted on the carrier 1 and equidistantly spaced around its periphery as will appear more fully below, are moved during one active step of said sprocket member from the position shown in Fig. 1 of the drawings through a distance equal to that between adjacent jaws, each jaw being thus moved to the position previously occupied by the one immediately preceding it.

Referring to these sets of jaws in greater detail, we have shown eight of them by way of example, mounted, as above noted at equal intervals about the periphery of the carrier 1. These jaws are preferably identical in construction, each of them preferably comprising a jaw element 7, rigidly mounted upon the carrier 1 in any desired manner not shown, and a yieldingly held jaw element 8 cooperating with element 7.

Element 8 preferably comprises a clamping portion 8', and a base portion 8² pivoted substantially centrally to the carrier as shown at 9. The said base portion 8² has a face 10 substantially parallel to clamping portion 8' and to one side of the pivot; and a second face 11, at an angle, when eight jaws are used, of 45 degrees to said clamping portion, and on the other side of the pivot. The face 10 of one jaw 8 is thus parallel to face 11 of the following jaw 8. A coil spring 12 is interposed between these parallel portions.

It is thus seen, that each jaw element 8 is under the control of two coil springs 12, both of which tend to hold jaw element 8 close to element 7 to thereby enable the jaws to firmly, yet yieldably, grip articles or

packages. The adjoining sides of jaw members 7 and 8 are preferably cut away, as shown at 13, for ready gripping of cylindrical packages or articles there between. Of course, articles of other shapes might be bound or labeled by our machine and for such purpose, the cut away portions 13 would preferably have different shapes, but it is to be understood that we prefer to employ our machine for the specific purpose set forth.

We prefer to feed into the jaws successively, cylindrical articles as shown at 14, each having a label or binder 15 thereabout, 15 with its ends projecting unequally therefrom as shown at 16 and 17.

As our invention is not concerned with the specific manner in which our package with the label projecting therefrom is fed to the machine, one method is simply suggested in the drawings by way of example. A platform 18 in alignment with the lower element of one of the jaws as indicated at 19, has mounted thereon a reciprocable plunger 20, 25 adapted to contact with one of the cylindrical articles and at the proper time to move forwardly, pushing said article between the jaw elements 7 and 8, with the wrapper 15 encircling substantially the more advanced 30 half of said package. By reason of the curved contour of the article the wrapper is thus firmly pressed into engagement with said half of said package when disposed between the jaws, the free ends 16 and 17 projecting from the package.

The label securing apparatus preferably acts upon the package when in the vertical position shown at 6°. This apparatus will now be described:

40 Pivoted preferably upon a rod 21 mounted on the frame of the machine, there is a bell crank lever having an arm 22 projecting downwardly and preferably carrying a paste roll 23 journaled thereto as at 40. The 45 other arm 24 of the bell crank, is connected by a cam rod 25, to be actuated therethrough by cam 26, the said cam rod having mounted thereon a cam roller 27 in engagement with the cam. The cam rod is preferably provided with a forked end 28, straddling the shaft 29, about which the said cam rotates, to prevent any substantial lateral deflection of said rod.

55 Pivoted about rod 21 and angularly displaced from arm 22, there is an arm 30 having a reversed extension arm 41, yieldingly pivoted thereto as shown at 32. The arm 41 has a tucking blade 31 rigidly connected to its outer end and projecting therebeyond, and said arm is further preferably provided with a shoulder 33 near its outer end for a purpose which will appear more fully below. The 60 arm 41 being thus pivoted at 32 to the arm 65 30 may partake of a slight movement about

its pivot 32 to automatically adjust the blade 31 with respect to the article or package, as will more clearly be hereinafter set forth.

A spring 34 connects arms 22 and 30, and a set screw 35 mounted on arm 30 abuts surface 36 on arm 22, thereby limiting the approach of said two arms. The tucking blade element 31 is preferably arcuate in form with its centre at the rod 21, which rod is so disposed that the movement of said tucking blade about said shaft, shall cause it to come substantially into tangential relation to the package or article when in the jaw elements at 6°. The slight curvature or the arcuate form given the tucking blade 31 permits the blade 31 to effectively clear the paste-applying roller 23 during the relative movements that take place therebetween, it being noted that the effective movements of both the blade 31 and the paste-applying 80 roller 23 preferably take place about the common center or pivot provided by the rod 21.

Concentric with the carrier member, we provide a stationary arcuate wall 37, of a 90 radius substantially equal to the distance of the outermost surface of the article or package from the centre of the carrier. The wall 37 is preferably yieldingly mounted with respect to the carrier 1 so as to urge the wall 95 member 37 substantially toward the center of the carrier 1. Thus, referring to Fig. 1, there is rigidly secured to the wall 37 a pin 37^a slidably engaging a member 37^b suitably rigidly held with respect to the carrier 1. 100 A spring 37^c is interposed between the wall 37 and the rigid member 37^b and tends to urge the wall 37 substantially radially inwardly with respect to the carrier 1.

Having thus described our construction, 105 the operation proceeds substantially as follows:

The machine being set into operation by any source of power, not shown, the carrier member is driven intermittently in a clockwise direction in Fig. 1, by the rotation of sprocket wheel 3. At any particular pause, the carrier member will occupy the position shown in Fig. 1, when a package or article 15, with a wrapper or label thereabout having its free ends projecting therefrom, is inserted between the jaws then in alignment with platform 18. This is preferably done automatically by plunger 20 and co-acting apparatus not shown, or by any other desired means.

When the carrier resumes rotation, the next jaw member is brought into alignment with platform 18 and a package or article is inserted therein with a wrapper partially 115 encircling it. In this manner, we prefer to feed a package and label to the carrier during every stop thereof.

A package or article with wrapper ends 120 projecting, is acted upon in the following 125

manner preferably when extending vertically upward as at 6':

The carrier having come to a pause, cam 26, which is timed for this purpose, causes cam rod 25 to be lowered by reason of cam roller 27, dropping to a more depressed part of the cam surface. Bell crank lever arm 24 is thus pulled downwardly and lever arm 22 to the right, thus carrying the paste roller 23 into proximity to the end of arcuate wall 37 and into engagement with the projecting end 17 of the label, thus applying paste thereto. In Fig. 1 the paste-roller 23 is shown in this position in dotted lines, and in Fig. 2 this relative position of the parts is more clearly illustrated. Arm 22 moving forwardly, arm 30 and the associated tucking blade 31, are drawn behind in the same direction because of the connection by spring 34, said tucking blade 31 coming into engagement with end 16 of the label, and drawing it about the package. Bearing in mind that the arm 41 carrying the tucking blade 31 is yieldingly pivoted at 32 to the operating arm 30, the tucking blade 31 is thus permitted to partake of a relatively slight movement about the pivot 32 to permit its tucking end to engage the free wrapper end 16 and follow the contour of the package to more effectively draw the wrapper or label end 16 about the package. At this time, before the tucking blade has completed its function, enlargement 33 abuts the stationary article as shown at 39, whereby further movement of the tucking blade is prevented. As soon as the carrier 1 resumes rotation, however, the spring 34, being still under expansion, will contract to cause the tucking blade 31 to follow the movement of the article, thus firmly holding the end 16 of the label in engagement with the article or package. The pivotal mounting of the tucking blade 31 through the arm 41 during this continued follow-up movement permits the latter to take place with positive and reliable result. Throughout this time, the paste roll remains in stationary position, applying paste to the end 17. As the carrier 1 continues movement, the article moves under the relatively stationary arcuate wall 37, which relative movement then causes the free end 17 to be wrapped about the article. As soon as the paste carrying end 17, comes into engagement with the extremity of end 16, as in Fig. 4 cam 26 operates to raise cam rod 25, thus withdrawing the tucking blade 31 and the paste roll 23 by an operation the reverse of that described in connection with the application of these elements to the packages.

The continued movement of the carrier causes the article 15 to move tangentially under the wall 37, thus firmly and tautly applying the free paste carrying end 17 over end 16, and thus completing the wrap-

ping operation. The wall member 37, it will be noted, provides a substantially continuous surface with which the overlapping label end 17 engages during the relative movement that takes place therebetween, thus affording a relatively great frictional action to insure the positive drawing of the overlapped end 17 about the article. Moreover, the spring 37, in yieldingly urging the wall 37 inwardly toward the carrier 1, permits the wall 37 to automatically adjust itself with respect to the carrier and hence with respect to the article or articles acted upon to compensate for variations or differences between articles successively operated upon. Moreover, the spring insures the positive frictional action above described to take place throughout such variations or differences.

When the wrapped article reaches the next stop, another operation or operations may be performed thereon, but as such operations are no part of our present invention, they are neither shown nor described.

The paste roller 23 is formed of suitable material and is practically at the bottom of the paste can 42. It is intermittently rotated at each oscillation of the arm 22 by means of a ratchet 43 co-acting with a swinging rack 44. There is thus continuously presented a fresh paste surface on the roll which sweeps over the end 17 of the label with which it comes in contact.

It is understood that when the article is completely wrapped, it may be withdrawn manually from the machine, or some automatic delivery mechanism may be employed. Such mechanism, however, being no part of our present invention, it is also neither shown nor described.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described our invention, what we claim as new and desire to secure by Letters Patent is:—

1. In a wrapping machine or the like, in combination, a work carrier having a plurality of supports, each adapted to hold an article to be wrapped and a wrapper therefor, means for causing said carrier to move intermittently and to carry therewith an

article and its wrapper, means operative at each stoppage of said carrier to tuck a wrapper about its associated article and means operative at said stoppage for applying paste to said wrapper.

2. In a wrapping machine or the like, in combination, a movable work carrier having a plurality of package holding supports, means for moving said carrier, means for placing a package and a wrapper upon said supports disposed in proximity to said carrier and at one point in the path thereof, means including a paste applying device and wrapper tucking devices disposed in proximity to said carrier and at another point in the path thereof and means for causing said package and wrapper placing means to operate on each support and said paste applying device and said tucking devices to operate on each wrapper as said respective parts are moved into alignment with said means and said devices by said carrier.

3. In a wrapping machine or the like, in combination, a rotatable work carrier, an arcuate tucking blade pivoted at substantially the center of its arc but externally of said rotatable work carrier, and adapted to assume a position substantially tangential to said carrier, means for periodically arresting said carrier with an article and partially applied wrapper therefor at a predetermined point in space, and yielding means for thereupon moving said tucking blade about its pivot, to fold a wrapper end projecting beyond said article, about the same.

4. In a wrapping machine or the like, in combination, a work carrier adapted to receive a package thereon having a freely projecting wrapper edge, a movable paste reservoir, a roller in operative relation to said reservoir and bodily movable therewith to apply paste to said free edge and means for folding said edge against said package to be pasted in place.

5. In a wrapping machine or the like, in combination, a movable work carrier, means to cause it to stop periodically with a package thereon and a free wrapper edge projecting from said package at a predetermined position in space, a paste reservoir, a paste roll, means for bodily moving said paste roll with said paste reservoir at each pause against said free edge, and means for folding said edge against said package to be pasted in place.

6. In a wrapping machine or the like, in combination, a movable work carrier, means to cause it to stop periodically with a package thereon, and a free wrapper edge projecting therefrom at a predetermined point in space, a platform back of said free edge, a paste roll, and means for causing said paste roll to move bodily to press said free edge against said platform, thereby applying paste to said edge, and means for there-

upon causing relative movement between said platform and said package in order to fold said edge against said package to be pasted in place.

7. In a wrapping machine or the like, in combination, a work carrier adapted to receive a package thereon having two freely projecting wrapper ends, a tucking blade for folding one of said ends against said package, a roll for applying paste to the other of said free ends and means for then folding said end against said package to paste it upon said first end.

8. In a wrapping machine or the like, in combination, a rotatable work carrier, a tucking blade pivoted externally of itself and of said carrier and adapted to assume a position substantially tangential to said carrier, a paste roll, an arm to which said roll is journaled, said arm being pivoted coaxially with said tucking blade, means for periodically arresting said carrier with an article at a predetermined point in space, and with two free wrapper ends projecting therefrom, and means actuated upon each pause for moving both said tucking blade and said paste roll about said pivot, to cause tucking of one said wrapper end, and application of paste to the other, and means to thereupon fold said latter end over said former.

9. In a wrapping machine or the like, in combination, a work carrier adapted to receive a package thereon having a freely projecting wrapper end, a tucking blade, means actuating said tucking blade to fold said wrapper end against said package, and means for subsequently actuating said tucking blade to press the extreme end of said wrapper against said package.

10. In a wrapping machine or the like, in combination, a rotatable work carrier, means to cause it to stop periodically with a package thereon, and with a free wrapper edge projecting therefrom at a predetermined point in space, a tucking blade actuated substantially at each pause to fold said wrapper end against said package, means positively arresting said blade before its function is completed, and means for subsequently causing said tucking blade to yieldingly advance in order to tightly press said entire free edge about said package.

11. In a wrapping machine or the like, in combination, a work carrier adapted to receive a package thereon having two freely projecting wrapper ends, a tucking blade and a paste roll, means actuating said tucking blade to fold one said wrapper end against said package, means actuating said paste roll to apply paste to the other said end, means to advance said tucking blade to draw the extreme edge of said first end tightly against said package, and means actuated substantially simultaneously with

said means last mentioned to apply said second or pasted end over said first end.

12. In a wrapping machine or the like, in combination, a work carrier adapted to receive a package thereon having two freely projecting wrapper ends, a paste roll, a tucking blade, means for moving said paste roll against one said wrapper end, a yielding connection between said means and said tucking blade, to urge the latter against the other said end for folding the same about the package, positive means for arresting said tucking blade before it has completed its function, means for removing said positive means to cause said tucking blade to advance to draw the extreme edge of said first end tightly against said package, and means actuated substantially simultaneously with said means last mentioned to apply said second or pasted end over said first end.

13. In a wrapping machine or the like, in combination, a work carrier adapted to receive a package thereon having two freely projecting wrapper ends, a paste roll, a tucking blade, means for moving said paste roll against one said wrapper end, a yielding connection between said means and said tucking blade, to urge the latter against the other said end for folding the same about the package, positive means on said carrier for arresting said tucking blade before it has completed its function, means for moving said carrier to permit said tucking blade to complete its function, and stop means simultaneously cooperating with said carrier to draw said pasted end over said tucked end.

14. In a wrapping machine or the like, in combination, a work carrier means mounted on said work carrier adapted to receive and hold a package thereon having a freely projecting wrapper end, a wall member means yieldingly mounting said wall member tending to urge it toward said holding means, and means to cause relative movement between the surfaces of said package and said yieldingly mounted wall member, tangentially to each other to press said projecting end into place.

15. In a wrapping machine or the like, in combination, a rotatable work carrier, means mounted on said work carrier adapted to receive and hold a package thereon with a free projecting wrapper end, an arcuate wall member substantially concentric with said carrier and substantially tangential to the path of said package as said carrier rotates, yielding means mounting said arcuate wall member and tending to urge it substantially inwardly and toward the axis of said rotatable work carrier, and means for moving said carrier to cause relative movement between the surfaces of said package and said yieldingly mounted wall member to take place, whereby said free wrap-

per end is drawn into firm engagement with said package.

16. In a wrapping machine or the like, in combination, a movable work carrier adapted to receive a package thereon with two freely projecting wrapper ends, a tucking blade, means actuating said tucking blade to fold one of said wrapper ends against said package, a connection between said actuating means and said tucking blade adapted to permit said tucking blade to adjust itself with respect to said package during movement thereof by said actuating means, and a stationary wall member substantially tangential to said package adapted upon movement of said carrier to fold and firmly draw the other of said wrapper ends about said first-mentioned wrapper end.

17. In a wrapping machine or the like, in combination, a movable work carrier, means to cause it to stop periodically with a package thereon, and with two free wrapper ends projecting therefrom at a predetermined point in space, an arcuate tucking blade normally to one side of said point, means to move said blade about the center of its arc in a path substantially tangential of said package, to tuck down one said wrapper end, an arcuate wall member having a non-yielding surface substantially concentric with said carrier member, and substantially tangential to the path of said package as said carrier is moved and means for moving said carrier to cause relative movement between the surfaces of said package and said wall member, whereby said other free wrapper end will be drawn into firm engagement with said package.

18. In a wrapping machine or the like, in combination, a rotatable work carrier, means to cause it to stop periodically with a package thereon and with two free wrapper edges projecting therefrom, at a predetermined point in space, an arcuate wall having an end adjacent said point, said wall being substantially concentric with said carrier member, and substantially tangential to the path of said package as said carrier rotates, a tucking blade and a paste roll, means actuating said tucking blade during one said stop to fold one said wrapper end against said package, means, simultaneously actuating said paste roll to apply paste to the other said end, whereby when said carrier resumes movement said wall will draw the paste carrying end into engagement with the edge of the tucked end, means for thereupon withdrawing said tucking blade and said paste roll, to allow said wall to complete the application of said wrapper, by movement of said carrier relative thereto.

19. In a wrapping machine or the like, in combination, a work carrier adapted to support an article thereon with a wrapper, means for placing on said carrier an article

and a wrapper related to one another so that one end of said wrapper projects substantially away from said carrier, means on said work carrier adapted to hold said article and associated wrapper in said predetermined relation, a wall member, and means adapted to cause relative movement between the surface of said package and the surface of said wall member tangentially with respect to one another to press said projecting end into place.

20. In a wrapping machine or the like, in combination, a movable work carrier having a plurality of article holding supports, means for moving said carrier, means for placing an article and a wrapper upon said supports related to one another so that one end of said wrapper projects freely from said carrier and disposed in proximity to said carrier and at one point in the path thereof, means associated with each of said supports adapted to cause said holding means to maintain said article and associated wrapper in said predetermined relation, and a wall member disposed in proximity to said carrier and at another point in the path thereof and adapted upon movement of said work carrier to press said projecting wrapper end in place about said article and to be operative after said pressing operation to draw tightly the pressed wrapper ends about a plurality of articles on said work carrier.

21. In a wrapping machine or the like, in combination, a movable work carrier adapted to receive an article thereon having two freely projecting wrapper ends, a tucking blade, means for moving said tucking blade against said article to fold one of said wrapper ends against the article, means pivotally connecting said tucking blade to said moving means to permit movement of said tucking blade to take place in a direction substantially transverse to the direction of movement given thereto by said moving means,

and means for folding the other of said wrapper ends about said first-mentioned wrapper end.

22. In a wrapping machine or the like, in combination, a movable work carrier adapted to receive an article thereon having two freely projecting wrapper ends, a tucking blade, means for moving said tucking blade against said article to fold one of said wrapper ends against said article, means adapted to permit said tucking blade during its movement against said article to move in a direction transversely to the direction of said movement and substantially in a direction toward or away from said article, a wall member adapted upon movement of said work carrier to fold the other of said free wrapper ends over said first-mentioned end and to draw it into firm engagement with said article, and means yieldingly mounting said wall member and tending to urge it against said article during the movement thereof relative thereto.

23. In a wrapping machine or the like, in combination, a movable work carrier adapted to receive an article thereon having two freely projecting wrapper ends, a tucking blade, an arm adapted upon movement thereof to move said tucking blade against said article and to fold one of said wrapper ends against said article, means pivotally connecting said tucking blade to said arm adapted upon movement of said blade by said arm to permit said blade to move substantially transversely to the path of movement given thereto by said arm, and means for folding the other of said wrapper ends over and about said first-mentioned wrapper end.

In testimony whereof, we have signed our names to this specification this 4th day of March, 1919.

MILFORD B. FERGUSON.
EDWARD HAAS.
